(57) CLAIM

The ornamental design for a combined soap dispenser and bath brush, as shown and described.

DESCRIPTION

FIG. 1 is a front elevational view of the combined soap
dispenser and bath brush of the present invention;

FIG. 2 is a rear elevational view of the combined soap
dispenser and bath brush of FIG. 1;

FIG. 3 is a left side elevational view of the combined soap dispenser and bath brush of FIG. 1, the right view being a mirror image thereof;

FIG. 4 is a top plan view of the combined soap dispenser and bath brush of FIG. 1; and,

FIG. 5 is a bottom plan view of the combined soap dispenser
and bath brush of FIG. 1.
